United States Patent Office

Des. 233,120
Patented Oct. 8, 1974

233,120

CUP HOLDER

Theodore R. Dawson, 3794 Blossom Lane,
Odessa, Tex. 79760

Filed Mar. 27, 1973, Ser. No. 345,317

Term of patent 14 years

Int. Cl. D7—06

U.S. Cl. D7—71

Fig. 1.

Fig. 2.

Fig. 3.

Fig. 4.

Fig. 5

Fig. 6

Fig. 7

FIG. 1 is a perspective view of a cup holder showing my new design;

FIG. 2 is a top plan view thereof;

FIG. 3 is a front elevational view thereof;

FIG. 4 is a right side elevational view thereof;

FIG. 5 is a bottom plan view thereof;

FIG. 6 is a left side elevational view thereof; and

FIG. 7 is a rear elevational view thereof.

I claim:

The ornamental design for a cup holder, as shown.
